COMBINED RAIN SKIRT AND UMBRELLA COVER

John A. Vigorito, New York, N. Y.

Application March 8, 1950, Serial No. 148,281

3 Claims. (Cl. 2-211)

1

This invention relates to a combined rain-skirt and umbrella cover, and has for its object the provision of a convenient and useful article of wearing apparel which can be readily and easily employed as an umbrella cover and thus carried while fitted about an umbrella yet be readily available for use as a protective rain skirt when required.

An object of the invention is to provide a skirt which can be readily folded and compacted and contained within a wrapper or enclosure attached to the skirt, said wrapper and skirt being capable of being formed into tubular shape to thus be fitted around and enclose an umbrella and thus resemble the conventional umbrella cover.

More particularly, the invention contemplates the provision of a skirt in the form of a flat section of material having means by which it may be connected around the waist of the wearer, said skirt being provided with a cover member in the form of a flap dependent from its waist line, said cover member or flap being adapted to receive the skirt in folded condition and enclose the skirt and hold it compactly around an umbrella, the flap being provided with fastening means by which it may be formed into and maintained in bag-like shape to not only retain the skirt within it but to also form a cover for an umbrella in a manner to be hereinafter described.

These and other objects are attained by the invention, a more particular description of which will be hereinafter set forth and pointed out in the claims appended hereto.

In the accompanying drawing, wherein an illustrative embodiment of the invention is disclosed, Fig. 1 is a face view of the improved rain skirt and umbrella cover, looking at the inner face of the same; Fig. 2 is a view showing the first step in the act of folding the skirt preparatory to enclosing it within its cover member; Fig. 3 shows the skirt partly folded; Fig. 4 shows the skirt fully folded and held under the retaining band provided on the cover member; Fig. 5 is a sectional view, taken on the line 5-5 of Fig. 1, looking in the direction of the arrows, and Fig. 6 is a perspective view showing the skirt and its cover fitted on and acting as an enclosure or cover for an umbrella of the folding or collapsible type.

Referring to the drawing, 1 indicates the body of the skirt, which is preferably of thin, easily-folded or compacted waterproof or water-repellant material, such as a proofed textile fabric or any one of the known water-repellant plastic materials now used for raincoats, umbrella coverings and the like. The skirt may be made in

2

the form shown or in many other styles and it is preferably composed of a flat section of material 1, provided at the top with a waist-band 6, which may enclose an elastic contracting member 7 to hold the garment properly about the waist of the wearer. The side edges 2 and 3 of the skirt are adapted to at least slightly overlap when the garment is worn and can be held in a closed or overlapped relation by means of the co-operating snap fastener elements 4 and 5 or other suitable fastening means.

Attached to the waist band portion 6 in any suitable manner, as by a line of stitching 9 if the nature of the material of the skirt permits 15 of stitching, or by fusing or other means, is the cover member 8 which is thus solely attached at the waist band and is in the form of a dependent flap normally overlying the inner face of the skirt and if the skirt is of non-transparent material 20 will be thus concealed from view when the skirt is being worn. Said cover member or flap 8 is provided along its edges with a slide fastener 11 which, when closed, converts the normally-flat flap 8 into a tubular casing or enclosure containing 25 the skirt and also an umbrella of the foldable or collapsible type as seen in Fig. 6.

The steps of folding the skirt to an extent required to compact it sufficiently to fit within the cover member 8 and to also permit the 30 umbrella to be positioned within the folded skirt, are shown in Figs. 2 to 4 inclusive. In Fig. 2 the side portions of the skirt have been infolded to overlie the backface 20 of the cover member or flap 8. The folded skirt is next upturned substantially along the transverse fold line 12 so that the skirt then becomes doubled on itself as seen in Fig. 3.

The folded skirt, now in the position shown in Fig. 3, is next transversely folded on itself along 40 the transverse fold line 13 so that the skirt is then of a compacted size slightly smaller than the cover member or flap 8. The folded or compacted skirt is now turned over to bring it against the front face 21 of the cover member or flap 8, 45 which face of the flap is provided with a transverse band 10 under which the folded skirt is tucked to place it in the position shown in Fig. 4. The umbrella 14, which is preferably, but not necessarily, of the collapsible or foldable type, 50 is now placed on the skirt and flap 8 and the slide fastener 11 is closed. The closure of the slide fastener results in the cover member of flap 8 being formed into a tubular, bag-like container enclosing the folded and compacted skirt 1 within 55 it and also forming an enclosure for the body of

the umbrella which becomes enclosed within the folded and compacted skirt. The material from which the skirt is formed is relatively thin, so that the folding of the skirt in the manner described does not add appreciably to the bulk of the umbrella cover. As a result, when the cover is placed in position on an umbrella as shown in Fig. 6, the wrapped or enclosed umbrella is unnoticeably larger in size than one enclosed in the conventional cover.

The arrangement described is such that when the umbrella is needed the cover member is readily removed; the skirt is unfolded and can be quickly donned by placing it around the waist and uniting the fasteners 4 and 5. The cover member or flap 8 may be worn on the inside of the skirt and will be unnoticeable, even if the skirt is of transparent material.

While I have shown and described one embodiment of the invention, it is obvious that the same is not to be restricted thereto, but is broad enough to cover all structures coming within the scope of the annexed claims.

What I claim is:

1. A combined skirt and umbrella cover comprising, a skirt body, a waist band thereon, the skirt body being in the form of a sheet having cooperating fastening elements at its opposite edges for interengagement to hold the skirt in tubular form about the body of the wearer, a flap of smaller size than the skirt having an upper edge attached along the waist band of the skirt, the flap being attached to the skirt only at said edge, a slide fastener extending along the remaining edges of the flap and adapted when closed to form the flap into a tubular cover to enclose the skirt and also enclose the body of an umbrella placed within the skirt, the flap being of a shape and size to enable it to enclose the

skirt in folded condition and to also enclose the body of the umbrella.

2. A combined skirt and umbrella cover comprising, a skirt body in the form of a flat sheet foldable to wearable tubular form and provided with fastening elements to retain it in such wearable tubular form, a flap of considerably less size than the skirt having an upper edge permanently attached to the upper edge of the skirt, the remaining edges of the flap being provided with fastening elements by the engagement of which the flap is formed into a tubular cover, the skirt being foldable to a size less than that of the flap whereby said skirt can be enclosed within the flap when the fastening means on the flap are closed, and an umbrella can have its body enclosed within the skirt and the cover thus formed, the flap being of a shape and size to enable it to enclose the skirt in folded condition and to also enclose the body of the umbrella.

3. In a combined skirt and umbrella cover, as provided for in claim 2, wherein the flap is disposed inside of the skirt when the skirt is worn, said flap being provided on one of its faces with a cross band under which the folded skirt is insertable.
